UNITED STATES PATENT OFFICE.

LEWIS P. HALLADAY, OF MARION, INDIANA, ASSIGNOR TO STREATOR METAL STAMPING COMPANY, OF STREATOR, ILLINOIS, A CORPORATION OF ILLINOIS.

CARPET-SWEEPER.

SPECIFICATION forming part of Letters Patent No. 764,050, dated July 5, 1904.

Application filed April 20, 1903. Serial No. 153,346. (No model.)

To all whom it may concern:

Be it known that I, LEWIS P. HALLADAY, a citizen of the United States, residing at Marion, in the county of Grant and State of Indiana, 5 have invented a certain new and useful Improvement in Carpet-Sweepers, of which the following is a specification.

My invention relates to carpet-sweepers, and has for its object to provide a new and improved device of this description.

My invention is illustrated in the accompanying drawings, wherein—

Figure 1 is a side elevation, with parts omitted, of a carpet-sweeper embodying my invention. Fig. 2 is a longitudinal section through one end of the device of Fig. 1, parts being omitted. Fig. 3 is a section on line 3 3, Fig. 1.

Like letters refer to like parts throughout the several figures.

20 The sweeper is provided with a case A, which instead of being formed as in the ordinary sweeper is a drawn-steel case. Along the sides of this case the metal is bent inwardly, forming the grooves A' and the inwardly-projecting ribs or parts A². The inner faces of these ribs or inwardly-projecting parts are located immediately above the dust-pans B, so that the dust-pans when closed project beneath them slightly. These dust-pans B are 25 pivoted to the outer edges or sides of the sweeper-case at the points B', and they open outwardly or downwardly, as indicated in dotted lines in Fig. 3. The brush throws the dust up during the operation of the sweeper, 30 and as it falls these ribs deflect it, as it were, and insure its falling into the dust-pans, and they also prevent any of the dust getting past the dust-pans over the backs thereof. These ribs also act as stops for the dust-pans to close 35 against and act, further, as stiffeners for the case. The grooves A' provide a place for the protecting tape or band A³, which extends about the sweeper.

The lower edge of the sweeper-case is bent 40 inwardly, so as to form a sharp edge A⁴. (See Fig. 3.) This sharp edge makes close contact with the lower corner of the dust-pan, said dust-pan being curved at this point, preferably forming the arc of a circle, so that when moved

to open and close it there is always close contact between the dust-pan and the inwardly-turned edge A⁴. This inwardly-bent edge also stiffens the case.

Between the brush C and the dust-pans B are provided the plates or strips B², against which the inner edges of the dust-pans close, said strips being preferably inclined outwardly and acting to keep the dust in the pan or pans when closed. The dust-pans are provided with a controlling device by means of which they 55 may both be simultaneously opened and closed. As herein shown, this controlling device comprises two pieces B³ B⁴, which are pivoted at one end to the dust-pans (see b, Fig. 3) and which pass up in proximity to the end of the 60 case and project through the top. These pieces are pivotally connected together at some convenient point, as at B⁵, and are provided at the end with an engaging piece B⁶, by means of which they may be pressed inwardly. The dust-pans are automatically returned to their initial position by means of some suitable retracting device, such as a 65 spring B⁷, which in this instance is a spring coiled around the support B⁸, attached to the 70 end of the case, the spring having its ends bearing on the under surface of the pieces B³ and B⁴. (See Fig. 3.) By means of this construction the dust-pans may be dumped or 75 unloaded by pressing down upon the part B⁶, for 80 in this event both pans are simultaneously moved outwardly about the pivots B'. When the part B⁶ is released, the spring moves the pans back to their operative position.

The brush C is provided at its ends with the 85 friction part or wheel C', which is engaged by the wheels C², which run upon the floor. The wheels C² are provided with axles or shafts C³, which, as herein shown, extend entirely across the case, so as to connect the two wheels 90 at the ends thereof. The openings in the case are larger than the shafts, so as to permit a certain amount of play, and the wheels are kept in contact with the friction part or wheel C' by means of a single spring D at each end, 95 said spring acting on both of the wheels at that end by engagement with the shafts thereof, so as to elastically force the wheels toward

each other, and hence toward the friction-wheel C'. The spring D, as shown, is a bent spring fastened at its middle by being coiled around a support attached to the end of the case, the free ends of the spring engaging the shafts of the wheels C'.

The bail E of the sweeper is provided with a ferrule E', which is drawn from sheet metal with the end E² formed solid and closed. A hole is made through the ferrule near this closed end, and the bail is passed through this hole, being in proximity to or in contact with the end E². The bail is then brazed to the ferrule and to the solid end thereof, thus forming a solid, durable, and fixed connection between the bail and the handle E³. It will be seen that by this construction instead of relying on the thin sides of the ferrule to resist the force applied to it there is provided this integral bottom or end E², and the end and sides forming a solid piece act together to resist the pressures and strains applied to the handle.

The ends of the case are indented, so as to

form the integral projections A⁷, between which the bail fits when in its central position. The bail being elastic may be sprung past these projections in either direction.

I have shown in detail a particular construction embodying my invention; but it is of course evident that the parts may be varied in many particulars. I therefore do not limit myself to the particular construction illustrated.

I claim—

In a carpet-sweeper, the combination of a case formed of sheet metal, the sides of which are bent inward to form external grooves and internal ribs, the protecting tape for the sweeper arranged in such grooves, and the brush and dust-pan mounted within the casing, the edge of the pan farthest from the brush being overhung by one of the said ribs, substantially as set forth.

LEWIS P. HALLADAY
